UNITED STATES PATENT OFFICE

MICHAEL SMOLENSKY, OF CLEVELAND, OHIO.

VALVE MECHANISM FOR PUMPS, COMPRESSORS, &c.

1,185,139.

Specification of Letters Patent. Patented May 30, 1916.

Application filed July 6, 1914. Serial No. 849,257.

To all whom it may concern:

Be it known that I, MICHAEL SMOLENSKY, citizen of the United States, residing at Cleveland, in the county of Cuyahoga and State of Ohio, have invented certain new and useful Improvements in Valve Mechanism for Pumps, Compressors, &c., of which the following is a specification.

This invention relates to valve mechanism for pumps, compressors or the like, and embodies an improved valve chest and a valve arrangement therein, said valves controlling ports or passages of novel arrangement or construction.

In the accompanying drawings, the invention is shown applied to hand pumps, but it can be applied to power pumps as well.

In the drawings; Figure 1 is a side elevation of a double-acting pump, showing the intake side. Fig. 2 is a vertical longitudinal section of the valve chest shown in Fig. 1. Fig. 3 is a partial end view of Fig. 1.

Referring specifically to the drawings, 6 indicates the pump cylinder and 7 the valve chest, which may be made either separate from or integral with the cylinder. In the figures it is shown integral. The piston 8 reciprocates in the cylinder. Communicating with the cylinder at either end (in the double-acting type), are ports 9 and 10 which open into corresponding valve cylinders 11 and 12, and 13 and 14. The cylinders 11 and 12 are located at an angle to each other, likewise the cylinders 13 and 14, the cylinders 11 and 14 being located in opposite axial alinement, and the cylinders 12 and 13 being located in parallelism, adjacent to each other, so that they stand side by side at or about the middle of the valve casing. This arrangement is convenient for communication with the outlet 29.

Within the respective valve cylinders are piston or sliding plug valves 15, 16, 17 and 18, the ends of which are tapered as indicated at 15', 16', 17' and 18', and adapted to seat against the tapered seats 11', 12', 13' and 14' of the respective valve cylinders. By-passes 19, 20, 21 and 22 are respectively provided in connection with the valve cylinders, these by-passes being cored in the valve casing to provide or establish communication around the valves under certain conditions. The valve cylinders are provided with and closed by suitable screw plugs 23, 24, 25 and 26, respectively. These plugs are

of cage construction, that is, they have openings communicating with the inlet and outlet passages 27 and 29, the inlet 27 being branched as indicated at 28, to connect with the opposite inlets at the opposite ends of 60 the casing. The outlet 29 opens from both of the outlet valve chambers, as above described.

In the operation of the double-acting pump, the piston moving to the left as shown 65 by the arrow in Fig. 2 will lift the valve 16 and close the inlet valve 15, the fluid passing through the by-pass 20 and through the openings in the plug 24 to the outlet 29, and at the same time fluid is drawn in through 70 the inlet 22, the valve 18 being drawn to position between the opposite ends of the by-pass 22 and opening the passage through the cage plug 26. The same action closes 75 the valve 17 against its seat, thereby closing the outlet passage 21. On the other stroke, the reverse operation takes place.

One of the advantages of the construction shown and described is that the valve chest (and also cylinder if desired) can be 80 cast in one piece, and any valve can be taken out or put in without disconnecting any pipe or disturbing other valves. This results from the middle connection of all the passages and the arrangement of the valve 85 cylinders with removable screw plugs at the outside of the casting, and the removable plug valves which may be slipped in or out of the bores. There is an absence of flat joints, gaskets and bolts in the whole valve 90 structure, so there is no chance for leaking.

What I claim as new is:—

1. A double-acting pump comprising a pump cylinder with ports communicating with opposite ends thereof respectively and 95 extending toward the middle thereof, and a valve chest having inlet valve cylinders each of which communicates at its inner end with one of said ports, and outlet valve cylinders each of which also communicates with one of said ports, and suitable valves in said valve cylinders, said valve cylinders being located in angular relation to each other, and provided with exteriorly removable closures at their outer ends and also 100 with lateral pipe connections at said ends.

2. A double-acting pump comprising a pump cylinder with ports communicating with opposite ends and extending toward the middle thereof, and a valve chest having in- 110

- let valve cylinders each of which communicates at its inner end with one of said ports, and outlet valve cylinders each of which also communicates at its inner end with one of 5 said ports, said inlet and outlet cylinders being located in angular relation to each other, and suitable valves in said valve cylinders, the inlet valve cylinders being located in opposite axial alinement, and the outlet 10 valve cylinders being located beside each other and communicating with the same outlet passage, each of said cylinders having a removable closure at the outer surface of the casing.
- 15 3. A pump valve mechanism comprising a valve casing having a cylinder therein, and a by-pass communicating at opposite ends with said cylinder, a valve movable in the cylinder and arranged to open or close said 20 by-pass, a hollow plug in the end of the cylinder, said plug having openings communicating with said cylinder to permit flow therethrough into the cylinder, and a lateral

inlet pipe to the cylinder communicating with said openings at a distance from the 25 by-pass, the valve controlling the passage through said openings and plug to the by-pass.

4. A pump valve mechanism comprising a valve casing having a cylinder therein, and 30 a by-pass communicating at opposite ends with said cylinder, a valve movable in the cylinder and arranged to open and close said by-pass, a hollow plug in the end of the cylinder, said plug being open at one end to 35 permit flow axially through the same to or from the cylinder and also having lateral openings for the passage of fluid so flowing, to or from the by-pass.

In testimony whereof, I affix my signature 40 in presence of two witnesses.

MICHAEL SMOLENSKY.
